(57) **CLAIM**

The ornamental design for a cell phone charging kiosk, as shown and described.

DESCRIPTION

FIG. 1 is a perspective view of a cell phone charging kiosk showing my new design.

FIG. 2. is a front view of the cell phone charging kiosk shown in FIG. 1.

FIG. 3 is a rear view of the cell phone charging kiosk shown in FIG. 1.

FIG. 4 is a right side view of the cell phone charging kiosk shown in FIG. 1.

FIG. 5 is a left side view of the cell phone charging kiosk shown in FIG. 1.

FIG. 6 is a top view of the cell phone charging kiosk shown in FIG. 1; and,

FIG. 7 is a bottom view of the cell phone charging kiosk shown in FIG. 1.

The broken lines shown in the drawings are for the purpose of illustrating portions of the cell phone charging kiosk that form no part of the claimed design.

1 Claim, 5 Drawing Sheets
